UNITED STATES PATENT OFFICE.

GEORGE H. LANG, OF BOSTON, MASSACHUSETTS.

NUMBERING OR MARKING MACHINE.

No. 877,653.

Specification of Letters Patent.

Patented Jan. 28, 1908.

Application filed May 14, 1907. Serial No. 373,579.

To all whom it may concern:

Be it known that I, GEORGE H. LANG, a citizen of the United States, residing at Boston, county of Suffolk, and State of Massachusetts, have invented an Improvement in Numbering or Marking Machines, of which the following description, in connection with the accompanying drawing, is a specification, like letters on the drawing representing like parts.

This invention relates to numbering or marking machines of that type comprising a numbering head having a plurality of adjusting type-disks therein which can be adjusted independently to make any desired combination of letters, numbers or other distinguishing marks. A numbering machine of this general type is shown and described in my co-pending application Se. No. 348,731, filed December 20, 1906.

One of the objects of my present invention is to provide a novel means for positively alining the type-disks after they have been set so that when the mark is printed by the machine the characters made by the various type-disks will be in accurate alinement with each other; and another object is to provide a device which not only alines the type-disks prior to the printing operation, but also positively locks them from movement during the printing operation so that it will be impossible to disarrange them after they have been set; and still another object of the invention is to provide a novel arrangement of the type-disks for printing letters, numbers and other characters.

In order to illustrate my invention I have chosen herein to show it as embodied in a numbering machine such as shown in my above-mentioned co-pending application although I wish it understood that the invention may be embodied in numbering machines having a different construction from that shown in my said application.

I will first describe one embodiment of my invention and then point out the novel features thereof in the appended claims.

In the drawings, Figure 1 is a longitudinal sectional view through a marking machine similar to that shown in my co-pending application but having my improvements applied thereto; Fig. 2 is a detail of the alining device. Fig. 3 shows the arrangement of type on the type disk.

The machine herein shown has the numbering head 3 carrying a plurality of type-

disks 4 which are rotatably mounted on the shaft 14 carried by the head but which project slightly below the head. The head is mounted on a vibrating arm 5 which is pivoted to the frame at 7 and which is operated by a crank-disk 9 that is connected to said arm by the link 8. Said crank-disk is driven by a gear 10 which meshes with and is driven by a gear 11 carried by the main shaft 38. The frame 2 carries the platen or bed 12 on which the material to be marked is placed and toward which the type head moves as the arm 5 vibrates.

The type-disks 4 are adjusted by means of segmental gears 17 mounted on a shaft 18 carried by the head and meshing with pinions or gears 16 rigid with the type-disks. Each segmental gear 17 has a thumb-piece 21 projecting through a slot in the numbering head and affording means by which the segmental gears and type-disks may be adjusted.

The parts thus far described are or may be all as shown in my co-pending application and form no part of my present invention.

In order to properly mark the goods it is essential that the type-disks be properly alined after having been adjusted, for if any type-disk is out of position the mark printed thereby will not be in alinement with the marks printed by the other type disks, and if any type-disk is sufficiently out of position two adjacent type thereon might both make an impression on the material thus causing an inaccurate mark to be made. As stated above, my invention aims to provide a novel device for accurately positioning the type-disks so as to aline the operative type thereon thereby preventing any inaccurate marking, which device will also positively lock the type-disks against movement during the printing operation.

In the present embodiment of my invention the type-disks are alined by an aliner 40 which is mounted on a yoke-shaped arm 41 that is pivoted to the arm 5, as at 42, and is adapted to swing toward and from the type-disks as the arm 5 vibrates. Each disk is provided with the aliner-receiving grooves or notches 43 situated between the adjacent type 15, and in the present embodiment of the invention these notches or grooves are V-shaped to correspond to the V-shape of the aliner 40.

For securing the movement of the aliner toward and from the type-disks I have shown a link 45 which is pivoted at one end to the

yoked arm 41 and at the other end has a pivotal connection with the standard 36, the arrangement of the link 45 being such that as the outer end of the vibrating arm 5 moves downward, the yoke 41 is swung forward to bring the aliner against the type-disks, as shown in dotted lines Fig. 1. During this forward movement of the aliner it enters the notches 43 in the disk and thus positively locks the disks against movement when the numbering head is in its lowered position and while said type-disks are making the impression on the material. If the type-disks are not accurately adjusted the 15 V-shape of the aliner, by engaging the V-shaped recesses or notches in the type-disks, serves to properly align them so that when the impression is made all type are absolutely in alinement.

20 I have herein shown the link 45 as having a sliding pivotal connection with the standard 36 so that in case any type-disk happened to be adjusted so that the aliner would strike squarely on the type, said aliner 25 would be permitted to yield backwardly and thus prevent the breaking of the parts. This sliding pivotal connection is afforded by the slot 46 in the link 45 in which is received the pin 47 on which the link 45 30 is pivoted.

44 is a spring which is secured at one end to the arm 5 and at the other end to the link 45. The tension of this spring is sufficient to hold the aliner in its forward position, as 35 shown in Fig. 1, with the pin 47 against the right-hand end of the slot 46 and to maintain the link in this position during the alining of the type-disks. If, however, a type-disk happens to be set so that the 40 aliner will strike squarely on one of the type during the printing operation, said spring will allow the aliner to yield rearwardly and thus prevent either breakage of the parts or injury to the type. If, however, the type-disks are adjusted approximately in the 45 proper position the aliner will perfect the proper alinement thereof and lock them in position while the impression is being made.

In the machine shown in my co-pending 50 application, a spring-pressed pawl is shown for holding the type-disks in their adjusted position. One difficulty with this arrangement is that the friction of the pawl on the gears of the type-disks makes it hard to 55 adjust said disks. In my present invention I have obviated the necessity for these spring-pressed pawls by the combined aliner and locking device herein shown, but in order to assist in approximately positioning 60 the type-disks as they are adjusted and to frictionally hold each type-disk when adjusted until it is locked by the aliner, I have shown a plurality of friction devices 50, one for each of the gears 17, and each adapted to 65 engage the toothed portion of the gear.

These friction devices are preferably made of spring metal and are secured to the casing of the head 3, and each bears against the teeth of the corresponding gear 17. The friction of the friction devices 50 is just sufficient to hold the gears in any adjusted position, but not sufficient to prevent the free and easy adjustment of the disks.

In making my device I propose to make the gears 16 with as many teeth as there are type on the type-disk and therefore the teeth on the gear 17 will be so spaced that the advancing of each gear the distance of one tooth will advance the corresponding type-disk one step. The friction of the friction devices 50 is such that when the gears 17 are adjusted the passing of the teeth over the spring 50 can be easily felt by the operator, and this construction will materially assist him in properly placing the disks.

In the marking of articles such as the articles in a laundry it is often desirable to mark thereon the initials of the owner's name as well as a number or other reference mark, and to permit this to be done I propose to employ in my numbering machine certain type-disks for marking letters and other type-disks for marking numbers or other characters. In some marking machines it has been proposed to arrange the type-disks with the letters of the alphabet in consecutive order divided between two adjacent type-disks. The difficulty of this arrangement, however, is that only a limited number of combinations of letters can be secured because of the fact that the alphabet is divided between two type-disks on the second of which there are other characters than the remaining letters of the alphabet.

In order to provide a printing head in which any desired combination of letters for initials can be produced, I propose to use a plurality, say two or three, type-disks on each of which all the letters of the alphabet are found and to employ a plurality of other type-disks which will have the digits thereon. As shown in Fig. 3 wherein five of the type-disks are developed, it will be seen that the type-disks *a* and *b* each have all the letters of the alphabet thereon, while the type-disks *d*, *e* and *f* each have the ten digits only thereon. Although this arrangement necessitates the use of twenty-six type on each of the type-disks *a* and *b*, yet this will not necessarily result in the type-disks 115 being unduly large because of the fact that the platen or bed 12 is comparatively narrow so that even though the type are set closely together upon the type-disk there will be no danger that more than one letter 120 or character at a time on each type-disk will contact with the surface which is to be printed upon as might occur if the bed or platen were a plain surface of considerable extent. The placing of all the letters of the alphabet 125

upon each of the type-disks *a* and *b* is a decided advantage over a construction in which the alphabet is divided between adjacent type-disks.

5 While I have herein shown my invention as embodied in a marking device such as shown in my co-pending application, I do not wish to be limited to this type of marking device as it will be obvious that the alining and locking device can be applied to other machines of this general character.

10 Having fully described my invention, what I claim as new and desire to secure by Letters Patent is:—

15 1. In a numbering or marking machine, the combination with a numbering head having type-disks and means to adjust said type-disks, of a vibrating arm on which said numbering head is mounted, a platen toward and from which the numbering head moves as the arm vibrates, a movably mounted type-disk aliner, and means to cause said aliner to move toward the type-disks while the numbering head is moving toward the platen and to be held out of engagement with the type-disk when the numbering head is in its elevated position.

20 2. In a numbering or marking machine, the combination with a numbering head having a plurality of type-disks, of a platen, a vibrating arm on which said numbering head is mounted, means to vibrate said arm thereby moving the numbering head toward and from the platen, a type-disk aliner carried by the arm, and means to hold said aliner out of engagement with the type-disks when the numbering head is entirely withdrawn from the platen and to move said aliner toward and into engagement with the type-disks when the numbering head moves toward the platen.

25 3. In a numbering or marking machine, the combination with a numbering head having a plurality of type disks, of a platen, a pivoted arm on which said numbering head is mounted, means to turn said arm about its pivot thereby moving the numbering head toward and from the platen, a type disk

30 aliner pivoted to the arm, a fixed support, and a link pivotally connecting said aliner to said support whereby when the numbering head is withdrawn from the platen, the aliner is held out of engagement with the type disks, while when said numbering head moves toward the platen the aliner is moved 35 into engagement with the type disks.

4. In a numbering or marking machine, the combination with a vibrating arm, of a numbering head having type-disks carried by said arm, a type-disk aliner pivoted to the 40 arm, a link pivotally connected to said aliner and having a sliding pivotal connection with a fixed support, and a spring connecting said link with said arm.

5. In a numbering or marking machine, 45 the combination with a plurality of type disks each having type thereon, of a gear rigid with each type disk, a segmental gear meshing with each of the first named gears, the teeth on said gears having such relation 50 to the type on the type disk that the advancing of each gear for the distance of one tooth will advance the type disk the distance of one type, and a friction device for each type disk engaging the teeth of one of 55 the gears for operating said disk.

6. In a numbering or marking machine, the combination with a plurality of type disks each having type thereon, of a gear 60 rigid with each type disk, a segmental gear meshing with each of the first named gears, the teeth on said gears having such relation 65 to the type on the type disk that the advancing of each gear for the distance of one tooth will advance the type disk the distance of one 70 type and a friction device for each type disk engaging the teeth of the segmental gear for 75 said type disk.

In testimony whereof, I have signed my name to this specification, in the presence of 90 two subscribing witnesses.
